FOLDING CARD TABLE

Filed Dec. 3, 1930

INVENTOR
John W. Beiger
BY *Campbell Ward*
ATTORNEY

UNITED STATES PATENT OFFICE

JOHN W. BEIGER, OF LUDINGTON, MICHIGAN, ASSIGNOR TO THE CARROM COMPANY,
OF LUDINGTON, MICHIGAN

FOLDING CARD TABLE

Application filed December 3, 1930. Serial No. 499,653.

The objects of the invention are:

First, to provide a simple, strong structure for bracing the table legs in upright position.

Second, to provide an improved pivoted brace means for such a table leg.

Objects pertaining to details and economies of construction and operation will appear from the description to follow.

A preferred embodiment of my invention is illustrated in the accompanying drawing, in which:

Fig. 1 is an inverted plan view of a card table embodying the features of my invention.

Fig. 2 is an enlarged detail inverted plan view of one corner of the table, showing the legs in folded position and the relation of the adjoining leg.

Fig. 3 is an enlarged detail side elevation view of one corner of the table showing the pivoted brace, a portion of the side rail being broken away to show the slide slot in the corner iron.

Fig. 4 is a detail sectional view on line 4—4 of Fig. 2, showing the spring clip for holding a leg in folded position.

The parts will be identified by their numerals of reference which are the same in all the views.

1 is the table top. 2 is the frame made up of side rails suitably joined together by a usual corner fastening. 3 is a corner iron bar inserted in each corner to strengthen the same and afford the support for the leg and the brace means.

One arm 31 of this corner iron has its outer end turned up into an ear 4. Pivoted ears 5, 5 are struck up from the corner iron towards the corner. 6 is the table leg which is pivoted to the ears 5 by the pivot 7. 8 is a main brace secured by pivot 9 to the bracket 4 and by through pivot pin 10 to the table leg.

11 is the pivoted brace for the table leg, being pivoted to the opposite end of the through pin 10. The upper end of this brace is provided with fixed cross pin 12.

Arm 32 of the corner iron 3 is provided with slot 13 which is struck with the arm 11 as a radius when the table leg is upright, being slightly enlarged at its upper end.

The brace 11 is drawn inwardly from the table by spring 18 wrapped around the end of pin 10 and secured at 14 to the table leg and wrapped around the pivoted brace at 15, see Fig. 3.

The foot of each leg is provided with a rounded glide 16 which serves as a "dome of silence" when the table is upright and which engages spring clip 17 secured to the table top when the table is folded.

Brace 8 is deflected and bent into close proximity to the side of the table leg 6 so that the adjoining table leg can be folded into position without interference.

The pivot pins 9, 7 and the pin 12 are in alignment when the table leg is folded, and pivot in line until the leg is swung to the upright position, when, due to the action of the spring 13, brace 11 swings out, carrying pin 12, to the end of the slot with a snap, locking the table leg in upright position where it remains until the brace 11 is moved back by the hand of the operator when the table leg can be folded.

The spring action swinging the brace outwardly so that the pin engages the end of the slot prevents any accidental displacement of the said brace, or at least tends to retain the brace in position and lock the leg upright until the pin 12 is moved into alignment with the pivot pins 9 and 7.

The pivoted locking brace is available with other structures than that here illustrated, but cooperates especially well with the opposing brace being secured to the same through pin.

By disposing the axis of the leg at a slight angle to the side rails, the end of the leg closes at a considerable distance from the side rail of the table, making it possible to dispose the brace and pivot it to the corner iron as shown.

I desire to claim the invention in the specific form illustrated on account of its compactness and simplicity and also broadly as pointed out in the appended claims.

Having thus described my invention, what I claim as new and desire to secure by Letters Patent is:

1. In a folding card table, the combination

of a top, a frame composed of side rails, a corner iron within the said side rails, one arm thereof having an upturned pivot lug at its inner end and a pair of pivot ears struck up towards the corner, a table leg pivoted at its upper end to the said ears, a brace secured to the said table leg and pivoted to the end lug, a pivoted lock brace pivoted to the side of the table leg and carrying an outwardly projecting pin at its upper end, a slide slot formed in the other arm of said corner iron described by the radius of the said lock brace when the table leg is in upright position, and a spring on the said brace arm to swing the same outwardly to cause the pin to engage the end of a slot.

2. In a folding card table, the combination of a top, a frame composed of side rails, a corner iron within the said side rails, one arm thereof having an upturned pivot lug at its inner end and a pair of pivot ears struck up towards the corner, a table leg pivoted at its upper end to the said ears, a brace secured to the said table leg and pivoted to the end lug, a pivoted lock brace pivoted to the side of the table leg and carrying an outwardly projecting pin at its upper end, and a slide slot formed in the other arm of said corner iron described by the radius of the said lock brace when the table leg is in upright position.

In witness whereof I have hereunto set my hand.

JOHN W. BEIGER.
